UNITED STATES PATENT OFFICE.

CHARLES F. ROOT, OF RAVENNA, OHIO, ASSIGNOR OF ONE-FOURTH TO BYRON O. CONN,
OF MANSFIELD, OHIO.

SAFETY DEVICE.

1,298,567.

Specification of Letters Patent. Patented Mar. 25, 1919.

Application filed October 5, 1914. Serial No. 864,974.

To all whom it may concern:

Be it known that I, CHARLES F. Root, a citizen of the United States of America, residing at Ravenna, in the county of Portage 5 and State of Ohio, have invented certain new and useful Improvements in Safety Devices, of which the following is a specification.

This invention relates to certain new and 10 useful improvements in safety devices for staying machines, though equally applicable to any character or type of machine which has a reciprocating work engaging element, as for example a punching press.

15 The object of my invention is to provide means for automatically preventing the link that imparts movement to the reciprocating work engaging element from operating when an obstruction is inadvertently or otherwise placed between the element and the 20 anvil and upon engagement of the element with the obstruction.

It is well known in the operation of machines that are provided with a reciprocating work engaging element which exerts a pressure upon an anvil, die or the like, that 25 there is great danger of the operator's fingers being inadvertently placed between the anvil or die and the reciprocating element that exerts pressure to perform the work, 30 with the result that the fingers are crushed or injured.

This is especially true when it is necessary for the operator of the machine to perform work that requires him to place his 35 hands in close proximity to the anvil or die of the machine, and in manipulating the work his hand is liable to be engaged by the reciprocating working element at the time 40 the latter is about to perform its work.

The primary object, therefore, of my invention is to provide means of relieving the pressure that is exerted by the reciprocating element upon the anvil or die to perform the 45 work when an obstruction is interposed between the anvil or die and the reciprocating element.

The primary object of the invention is to provide a machine of the type set forth with

mechanical means embodied in the reciprocating element, which automatically causes the element to remain inoperative, if in its descent any obstruction, such as the hand of the operator, or one of the fingers of the hand, is met with. 50

Further, the invention aims to provide means which is incorporated in the reciprocating element so as to only render the latter operative, or rigid, just prior to or at the instant of commencement of the punching, 55 pressing, forming or stamping operation, or in other words, only at the instant that the reciprocating element is about to enter into actual or physical contact with the work. 60

Still further, the invention aims to provide means which is sensitive to operation by the finger or hand of the operator, should the finger or hand be in a position 65 subject to injury by the reciprocal element, 70 without actual injury to the finger or hand.

Further, the invention aims to provide a structure which can be adjusted to operate in connection with material possessed of varying thicknesses. 75

The objects above described are set forth in Letters Patent granted to me bearing date of March 9, 1915, Patent Number 1,131,161 and pending application bearing Serial No. 857,016, filed August 17, 1914, 80 and the present application has the same objects in view in general but includes improvements in the structure described in said applications and consists in the following new features, to wit: 85

Cam actuated means to positively render the reciprocating element inoperative until it reaches a predetermined point in its working stroke and means to render said reciprocating element operative at said predetermined point or just prior to said element acting upon the work. 90

A further object is to provide a safety device for connecting the reciprocating element with its actuating means that is self 95 contained and that can be applied without making any changes or alterations in machines already in use which are provided

with reciprocating working elements such as punching presses, printing presses, staying machines and the like.

Another object is to provide a safety device for actuating the reciprocating element of the class of machines described that will be rendered inoperative, until it reaches a predetermined point in its working stroke, to exert a pressure upon any obstruction extraneous to or interposed between said reciprocating working element and the work upon which it acts although a part or parts of the mechanism be out of repair, disarranged, or broken.

15 A further object is to construct a simple and effective safety device composed of minimum parts.

The essential feature of the invention comprises a link having a slot, a half link slideable in the slot, a disk having an actuating cam formed thereon, a pivoted locking bar to lock the link and half link, and means to move the bar to locking position when disengaged from the cam, the latter acting to normally hold the bar out of locking position.

A further object is to so construct, combine and arrange the mechanism of a safety actuating means for imparting a reciprocating movement to the work engaging element of a machine, that the friction of the parts in operation and their liability to become deranged will be reduced to a minimum so that a slight resistance or pressure exerted 30 upon the work engaging element by a finger or other obstruction extraneous to the work will render the work engaging element inoperative to exert working pressure.

Another object is to provide devices which 40 will give the very least amount of pressure on a finger or other obstruction extraneous to the work by reducing the friction of the parts to a minimum, also reducing to a minimum the chance of said parts becoming wedged.

I attain these and other objects by the mechanism illustrated in the accompanying drawings, in which:

Figure 1 is a front elevation of a conventional type of staying machine showing the invention applied thereto and also showing the finger of the operator interposed between the anvil (which has a paper box mounted thereon) and the reciprocating work engaging element;

Fig. 2 is a detail view, in rear elevation of the link, half link and locking bar, looking from the rear toward the front of the staying machine, showing the half link interlocked with the link by a pivotal locking bar in dotted lines and unlocked therefrom in full lines.

Fig. 3 is a side view partly in section showing the link, half link and locking bar,

and cam disk assembled, mounted upon a 65 bushing and connected to the disk and crank pin of the driving shaft.

Fig. 4 is a side elevation partly in section of Fig. 1 on a reduced scale.

Fig. 5 is a front elevation of a cam disk 70 showing a cam formed thereon.

Fig. 6 is a side elevation of Fig. 5.

In the drawings, the driving shaft 1 is provided with a disk 2 having a crank pin 3, the shaft being journaled in suitable bearings in the L-shaped arm 4 of a conventional type of a staying machine. Movement is imparted to the driving shaft 1 by the driving pulley 5. A head 6 reciprocates between the ways 7 and has a stud shaft 8 secured thereto. A follower or work engaging element 9 is securely attached to the head 6 and co-operates with the usual anvil 10 of a staying machine or the like.

For the purpose of connecting the stud 85 shaft 8 of the head to the crank pin 3 of the driving shaft 1, by means of which reciprocating movement is imparted to the head 6, link 11, which is adapted to be interlocked with and released from a half link 90 12 by the pivoted locking bar 13, is provided. The link 11 is cut away or reduced on one side thereof at 14, forming a shoulder or abutment 15, which is adapted to contact with the free lower end 16 of the locking 95 bar and off-set portion 17 thereof.

A bearing or bushing 18 is secured to the upper end of the half link 12 and has one end thereof slidably projecting into an oblong slot 19 which is formed in the upper 100 part 20 of the link 11. The bushing 18 is securely fastened to the half link 12 by pin 21 and supports the link 11 and half link 12 and in turn is loosely mounted upon the crank pin 3. The bushing 18 is also provided on one end with an annular flange 22 which fits into the counter-bored portion 23 of a disk 24.

The function of the above parts will be described more specifically hereinafter. 110

An aperture 25 is formed in one end of the link 11 to provide a bearing for the stud shaft 8 of the head 6. The locking bar 13 is pivoted to the half link 12 by the stud pin 26. A finger 27 is formed on the 115 upper end of the locking bar.

In assembling, applying and constructing my safety device, the disk 24 is counter-bored on one side, as shown at 28, to fit over the disk 2 which is carried by the driving 120 shaft 1, the crank pin 3 passing through an aperture 29 provided in the disk. A cam 30 is provided on one side of the disk 24.

In connecting and applying the device to a staying machine or the like, the bushing 18 is loosely fitted in the aperture 29 in the disk 24 so as to permit the disk to rotate upon the bushing, the annular flange 22 of

the bushing seating in the counter-bore 23 with the face 31 of the bushing flush with the face 31' of the counter-bore. The half link is then mounted upon and secured to 5 the bushing and the projecting end 32 of the bushing passed through the slot 19 of the link 11 thereby providing means for supporting and carrying said link.

The tang 33 of the half link is fitted to 10 slide between the guides 34 and 35. The locking bar 13 is pivotally mounted upon the half link by inserting the stud pin 26 in a suitable aperture formed in the tang portion 33 of the half link.

15 The locking bar is maintained in its proper place against lateral movement by its finger 27 which projects into a space (provided by the width of the cam) between the disk 24 and the upper portion of the 20 half link.

The operation of my device is as follows:

When movement is imparted to the driving shaft, the crank pin 3 imparts a combined oscillating and reciprocating movement to the link and the half link which supports the locking bar and at the same time imparts a rotary movement to the cam disk 24 upon which is formed the cam 30 and as the disk is rotated the cam between 25 the points 36 and 37 thereof contacts with the finger 27 of the locking bar positively forcing it to pivot upon the stud pin 26 thereby releasing the end 16 from its position in contact with the abutment 15 as 30 shown in Fig. 2 in full lines, and maintaining the locking bar in said released position until the cut away portion 38 of the cam is aligned with the finger 27 at which time the locking bar is permitted to pivot upon the 35 stud pin to the locked or dotted line position shown in Fig. 2.

The spring 39 contacts with and normally exerts a pressure against the lower end of the locking bar to force the end 16 and 40 off-set 17 in contact with the abutment 15 and end of the half link, or in locked position. After the crank pin has traveled to a predetermined point which is preferably to within $\frac{1}{8}$ of an inch of the end of its working 45 stroke, the end 16 of the locking bar 13 is forced by spring 39 to engage with the abutment or shoulder 15 and the off-set 17 with the abutment 15 and the end 40 of the half link 12 (as shown in dotted lines in 50 Figs. 2 and 3).

The face of the cam 30 is so arranged that when the crank pin is on its up-stroke and has traveled to a point within $\frac{1}{8}$ of an inch of the end of its down-stroke carrying the 55 link, half link, and locking bar, the cam will be in contact with the finger 27 forcing the end 16 of the locking bar in unlocked position as shown in full lines in Fig. 2, until the cut-away portion of the cam in its travel

reaches and then passes the finger 27 when 65 the locking bar is permitted to pivot and be forced in locked position by the spring 39.

The end 16 of the locking bar and its off-set 17 engage with the half link and abutment just before the work engaging element 70 reaches the end of its down-stroke to act upon the work and continue to be engaged therewith until the cam engages the finger 27. This operation is repeated upon each 75 revolution of the driving shaft 1.

If an obstruction, as for instance the finger 41 of the operator, is interposed or projected between the work engaging element 9 and the anvil 10, which finger is in thickness 80 in excess of an eighth of an inch (or any predetermined thickness) the downward stroke of the head will be arrested and the head and link will idle, the crank pin 3 completing its stroke by passing or moving, with the bushing 18, through the slot 85 19, since the end 16 and off-set 17 of the locking bar 13 cannot contact with the abutment or shoulder 15, as shown in full lines in Fig. 2, owing to its being in a position below shoulder 15 where it cannot engage 90 the shoulder 15 or end of the link 40 and therefore no pressure can be exerted upon the obstruction. A ball 42 is forced in contact with the side of the tang 33 of the half 95 link by a spring 43 to provide a slight friction to yieldingly hold the half link and end link in proper relative positions for engaging the locking bar and off-set.

Attention is called to the fact that the locking bar is positively held in unlocked 100 position by cam action until the working element reaches a predetermined point in its downward stroke, and that the cam can be readily attached to the end of the driving shaft without changing or altering the machine in any way and without the use of any appliances other than the device itself which is self-contained.

It will further be noted that the parts can 110 not be improperly assembled as they must be mounted and held upon the bushing in operative relation to each other preparatory to applying or attaching them to a staying machine or the like.

Attention is further called to the fact that 115 the off-set 17 is wedged between the end 40 of the half link and the abutment 15 when pressure is exerted upon the element and at the same time the end 16 of the half link is in contact with the abutment 15 to thus provide a firm footing or point of bearing of locking bar 13 on shoulder 15.

What I claim is:—

1. In a safety device, in combination with a reciprocating work engaging element, a 125 driving means, means to connect the driving means and work engaging element, a disk mounted on the driving means having a cam

formed thereon to maintain said connecting means inoperative, means on said cam to allow said connecting means to be rendered operative at a predetermined point in its 5 working stroke when the path of the element to the work is unobstructed, and means to actuate the connecting means to render same operative.

2. In a safety device, in combination with 10 a reciprocating work engaging element, and an anvil, a driving mechanism, means to connect said work engaging element to said driving mechanism, a removable disk connected to the driving means and having a 15 cam to permit the connecting means to be rendered operative at a predetermined point and means to actuate the connecting means to render same operative.

3. In a safety device, having a work engaging element and means for reciprocating same, a removable disk attached to said means for reciprocating the work engaging element and having a cam, and means controlled by the cam whereby the means for reciprocating the work engaging element is rendered inoperative until it reaches a predetermined point in its working stroke, and is rendered operative after it reaches said point and when the path of the element to the 30 work is free.

4. In a machine having a work engaging element and anvil, means for reciprocating said element including a link and half link relatively movable, a locking bar for locking 35 and unlocking said link and half link, a disk having a cam formed thereon attachable to the means for reciprocating the work engaging element for actuating the locking bar to unlock the link and half link and for allowing locking of the link and half link, and means to actuate the bar into interlocking 40 position when the path of the element to the work is free.

5. In a machine having a reciprocating 45 work engaging element and an anvil, a driving means, means comprising a full link and half link relatively movable to connect the driving means and reciprocating work engaging element, a locking bar adapted to be locked with and unlocked from said link and half link, means to move said locking bar from locking position, and means to actuate the locking bar to move the same to locking 50 position when the path of the element to the work is free.

6. In a machine having a reciprocating 60 work engaging element and an anvil, a driving means, means comprising a link and half link relatively movable to connect the driving means and reciprocating work engaging element, a locking bar adapted to be locked with and unlocked from said link and half link, a disk having a cam formed thereon attached to said driving means to move

the locking bar from locking position, means 65 to actuate the locking bar to move same to locking position when the path of the element to the work is free.

7. In combination with an anvil, a work 70 engaging element, and a driving means including an ordinary disk and eccentric pin, means to connect said work engaging element and driving means, means attachable to both the disk and pin without their modification to thereby fixedly support and position said 75 means to render said connecting means inoperative to prevent same from exerting pressure upon the anvil when an obstruction thicker than the work is interposed between the anvil and said element.

8. In a safety device for a machine having a work engaging element and an anvil, means to reciprocate the work engaging element to exert pressure upon the anvil including an ordinary disk and eccentric pin and 85 means attachable to both the disk and pin without their modification to thereby fixedly support and position said means to render said reciprocating means inoperative and to prevent same from exerting pressure upon 90 the work when the work engaging element is subjected to pressure by an obstruction extraneous to the work and which is in the path of travel of the work engaging element.

9. In a safety device for a machine 95 equipped with a reciprocating work engaging element and an anvil, driving means for said element, including an ordinary disk and eccentric pin, means to connect said driving means and work engaging element, means attachable to both said disk and pin without their modification, to thereby fixedly support and position said means to actuate said connecting means to exert pressure upon the anvil and means to render said connecting 100 means inoperative so as to prevent same from exerting pressure when the work-engaging element is subjected to pressure by an obstruction in its path of travel, thicker than the work.

10. In a safety attachment for a machine equipped with a reciprocating work engaging element and an anvil, a driving means including an ordinary disk and eccentric pin, means to connect said work engaging element 115 and driving means, means attachable to said disk and pin without their modification and removable from the driving means whereby said connecting means is rendered inoperative to exert working pressure when an obstruction thicker than the work is interposed in the path of the work engaging element, and means to render the connecting means operative to exert working pressure when the path of the work engaging element is 120 clear, except for the work.

11. In a safety device, in combination with a reciprocating work-engaging element and

an anvil, of driving mechanism, yieldable means connecting the work-engaging element and the driving mechanism, and means removably mounted on the driving mechanism for controlling the operation of the 5 yieldable connecting means.

12. In a safety device, in combination with a reciprocating work-engaging element and an anvil, of driving mechanism, yieldable 10 means connecting the work-engaging element

and the driving mechanism, and cam means removably mounted on the driving mechanism for controlling the operation of the yieldable connecting means.

In testimony whereof I affix my signature 15 in presence of two witnesses.
